UNITED STATES PATENT OFFICE.

KARL L. DIETERLE, OF LOS ANGELES, CALIFORNIA.

LIQUID-DISPENSING DEVICE.

1,228,758.

Specification of Letters Patent. Patented June 5, 1917.

Application filed April 10, 1916. Serial No. 90,037.

To all whom it may concern:

Be it known that I, KARL L. DIETERLE, a citizen of the United States of America, residing at Los Angeles, in the county of 5 Los Angeles and State of California, have invented a new and useful Liquid-Dispensing Device, of which the following is a specification.

This invention relates to a device for dispensing ether, or other liquids which require to be dispensed in a graduated or regulated manner, for example, drop by drop, and the main object of the present invention is to provide for regulation of the flow of the 15 liquid from the device and for uniformity of such flow when so regulated.

Another object of the invention is to provide dispensing means for the stated purpose, in which the container for the liquid 20 is hermetically sealed until the time of use.

A further object of the invention is to enable resealing of the container after each dispensing operation so as to prevent waste or deterioration of the liquid by evaporation 25 or otherwise.

The accompanying drawings illustrate an embodiment of my invention, and referring thereto, Figure 1 is a vertical section of the container provided with my improved dispensing means.

Fig. 2 is a vertical section of the container in inverted position, showing the dispensing means operated to dispense the liquid by drops.

Fig. 3 is a vertical section of a modified form of the invention.

1 designates a suitable container, which may be of sheet metal or other material, and may be provided with a neck 2 which is 40 closed by a cover 3 secured by solder or otherwise to the neck 2 after the liquid indicated at 4 is placed in the container, so as to hermetically seal the container, this cover 3 consisting, for example, of a disk or plate 45 extending completely over the neck to close the same.

The container is provided with means mounted thereon and supported thereby, for puncturing said cover, consisting, for example, of a screw 5 screwing in a boss or projection 6 on the cover 3 and provided with handle means such as a knurled head 7 and with a pointed end 8 adapted to puncture the central portion 3' of the cover 55 3, said central portion, at least, of the cover being made of comparatively soft metal so

as to be readily punctured. The knurled head 7 of the screw may be provided with a packing ring 9 adapted to engage the top of the boss 6 when the screw is screwed down 60 toward the same to form a tight joint. Screw 5 is preferably provided with a groove 11 extending longitudinally thereof for passage of liquid as hereinafter described.

In order to provide for entrance of air to the interior of the container for displacement of the liquid therefrom, a tube 12 is preferably provided extending from near the bottom of the container through the 70 cover 3 and normally closed at its outer end as indicated at 12' to maintain hermetic sealing of the container. This air vent tube is preferably formed of soft metal to enable it to be cut for breaking the seal and to be 75 resealed by compressing the end portion thereof.

The device is used as follows:—The air vent tube 12 is cut at its outer end to admit air thereto and the screw 5 is screwed down 80 so as to perforate the center portion 3' of the cover. The container is then inverted as shown in Fig. 2, and the ether or other liquid passes through the opening thus formed in the cover, the size of said opening 85 being regulated by screwing back the screw any desired extent so as to enlarge the opening between the point of the screw and the cover and, if necessary, to cause groove 11 to extend beyond boss 6 so as to facilitate 90 leakage of the liquid past the screw. The liquid will then drop from the head 7 at a definitely regulated rate so that the device, having been once set by a skilled operator, 95 the administration of the ether, for example, may be left to a comparatively inexperienced person with instructions to administer it for a certain time at the regulated rate.

When the container is inverted, as stated, air will pass through the air tube 12 to the upper part of the container displacing the liquid, which therefore flows from the container uniformly without interference due to difference of pressure on the inside and outside of the can.

When the dispensing operation has been completed the screw 5 is screwed down to bring the packing 9 into tight engagement with the boss 6 and the outer end of the vent tube 12 is pinched by a suitable instrument to close the same, the container being thereby sealed so as to prevent further es-

cape of liquid by evaporation or otherwise. When the device is to be used again an additional portion of the tube 12 is cut off, the tube being made long enough to permit several repetitions of this operation.

The cover member 3, with the vent tube 12, may be cast in one piece of suitable soft metal, and be afterward soldered on to the neck 2, or on to the surface of a can of any kind, over an opening therein. The cover being soft may be readily cut, if desired, to enable the ether can to be used with the usual cork or otherwise.

The puncturable cover member may be applied to the container in other ways. For example, as shown in Fig. 3, the said member, indicated at 16, may be secured to a cork 14 by means of a tubular projection 19 on said cover member fitting within a hole in said cork. The edge portion 17 of said cover member may be turned down or crimped to form a tight seal over a flange 18 on the neck 15 of a bottle 20 which may be a chloroform bottle. The construction is otherwise the same as above described, the cover member 16 being of soft metal and having a puncturable part 16' adapted to be penetrated by the pointed end of screw 5 in the same manner as above explained.

An important feature of this invention is that the means for puncturing the seal is permanently mounted on the container so that each container is provided with means for allowing the liquid contained therein to be dispensed, without requiring the use of an additional puncturing device.

A further feature of the invention is that the puncturing means is also adapted to coöperate with the punctured portion of the container, operating as a valve seat, to act as a regulating means for the flow of liquid after the container is punctured, and eventually to act as a closing and sealing means for the container.

What I claim is:—

1. A container for liquid, provided with a puncturable sheet metal seal portion, and a puncturing and regulating device mounted on and supported by said container to move toward or from said seal portion to puncture the same and to form a variable dispensing opening.

2. A container for liquids, provided with a puncturable seal portion, and a punctur-

ing means mounted on and supported by the container and formed as a screw having a pointed end, said puncturing means being mounted on said container to screw thereon so as to cause the point of the screw to puncture the seal, and to withdraw the point from the punctured part to form a variable dispensing opening.

3. A container for liquids, provided with a puncturable seal portion, a puncturing means mounted on and supported by the container and formed as a screw having a pointed end and screwing on said container to cause said pointed end to puncture the seal or to open or close the opening formed by puncturing the seal, and an air inlet tube extending from near the bottom of the container to the outside of the container, said air inlet tube being of soft metal and being of sufficient length outside the container to enable it to be repeatedly cut for opening the tube or pinched for closing the same, and said puncturing means being provided with packing means for tightly engaging the outside of the container to close the same.

4. A container for liquids, provided with a puncturable seal portion, a projection on the container, a screw working in said projection and having a pointed end adapted to puncture the seal portion and to coöperate therewith as a valve, and a normally closed air inlet tube communicating with the interior of the container and consisting of easily cut material to enable it to be opened for admission of air.

5. A container for liquids, having a portion formed with a screw threaded opening, a puncturable seal normally closing said opening, a screw working in said screw threaded opening and having a pointed end adapted to puncture said seal and to coöperate with the punctured portion to form a variable dispensing opening, said screw having a longitudinal groove for enabling liquid to pass the screw, and said screw having an operating head and provided with a packing member on said head to engage the portion of the container around the screw threaded opening, to provide for tight closure of the container.

In testimony whereof I have hereunto set my hand, at Los Angeles, California, this 23rd day of March, 1916.

KARL L. DIETERLE.
